GAME CLOTH

Philip Youngman-Carter, 91 Great Russell St.,
London W.C. 1, England

Filed Feb. 5, 1960, Ser. No. 59,281

Term of patent 14 years

(Cl. D34—5)

The FIGURE is a plan view of a game cloth of conventional thickness showing my new design. The dominant feature of my design resides in the portion shown in full lines.

I claim:

The ornamental design for a game cloth, as shown and described.
